CLAIM

The ornamental design for an eyelash curler, as shown and described.

DESCRIPTION

FIG. 1 is a front elevational view of an eyelash curler showing my new design;

FIG. 2 is a top view thereof;

FIG. 3 is a right side elevational view thereof of which the left side elevational view is a mirror image thereof;

FIG. 4 is a rear elevational view thereof; and,

FIG. 5 is a bottom view thereof.
